UNITED STATES PATENT OFFICE.

FRANK S. DAVIS, OF DETROIT, MICHIGAN.

DESIGN FOR AN AUTOMOBILE-BODY.

No. 38,946.

Specification for Design.

Patented Dec. 10, 1907.

Application filed March 1, 1907. Serial No. 360,112. Term of patent 7 years.

To all whom it may concern:

Be it known that I, FRANK S. DAVIS, a citizen of the United States, residing at Detroit, in the county of Wayne and State of Michigan, have invented a new, original, and ornamental Design for Automobile-Bodies, of which the following is a specification, reference being had to the accompanying drawing, forming part thereof.

Figure 1 of the drawing is a side view of an automobile body constructed according to my design, and Fig. 2 is a rear view.

I claim

The ornamental design for an automobile body, as shown.

FRANK S. DAVIS.
